HIGH-VOLTAGE RECTIFIER

Otto H. Schade, West Caldwell, N. J., assignor to
 Radio Corporation of America, a corporation
 of Delaware

Application July 14, 1945, Serial No. 605,131

19 Claims. (Cl. 321—15)

1

This invention relates to a new and useful electrical condenser of the high voltage high frequency type for use with high frequency industrial oscillators and the like.

An object of this invention is to provide an improved low cost light weight condenser of the Leyden jar type wherein the inner electrode coating exceeds the outer electrode coating in its physical length to give an increased creepage path by having an external uncoated skirt to aid in preventing corona discharge.

Another object of this invention is to provide a condenser which will be made part of the actual circuit connections by combining the condenser with high voltage rectifiers of the electron discharge type which are frequently employed in a three stage voltage multiplier or tripling circuit.

Still another object of this invention is to provide an improved electrostatic condenser of the Leyden jar type which has increased electrical capacity for the same physical dimensions, and greater mechanical and electrical strength than those of the prior art.

A feature of this invention is the novel arrangement and shape of a condenser wherein the device has a re-entrant and reduced long necked portion which permits telescoping and capacitive variation with adjacent condenser units of similar shape.

Although electric condensers of the Leyden jar type are very old in the art, they are now infrequently used because of their bulk relative to the unit of electrical capacity. Also corona discharges cause ionization and consequent heating and power loss in the air and glass dielectrics. The Leyden jars of the prior art frequently break down by an electrical puncture through the glass wall between the inner and outer electrodes at the end of each coating. This invention overcomes the objection of the prior art condenser by providing a flask shaped condenser having a re-entrant portion, the outer portion of which is provided in the central dome portion. An encircling skirt decreases the tendency to form corona discharge at the termination of the outside electrode. The wall thickness is increased and curved at the portion where the skirt joins the cylindrical portion of the flask at the termination of the outer electrode. The outer electrode itself is rounded over at the electrode termination to further assist in the reduction of corona losses or electrical brush discharge.

The condensers of this invention have been found to be capable of standing continuous op-

2

eration in high frequency rectifier service at voltages in excess of 50,000.

This invention will best be understood by referring to the accompanying drawing in which:

5 Fig. 1 is a longitudinal section of a condenser of this invention; also the showing of the telescoping of other similar adjacent condensers.

Fig. 2 is a cross section view taken on line 2—2 of Fig. 1.

10 Fig. 3 is a circuit arrangement of the series connection of the condensers of Fig. 1.

Fig. 4 is a partial longitudinal section of the top end portion showing a method of making a connection between the inner electrode and the outer electrode of an adjacent condenser.

Fig. 4A is a partial elevation of Fig. 4.

Fig. 4B is a partial longitudinal section of a condenser of this invention showing another method of making connection to the inner electrode of a condenser.

20 Fig. 5 is a schematic showing of a voltage multiplier circuit employing the condenser of this invention; and

Fig. 6 is a circuit diagram of a voltage multiplier.

25 Referring now in detail to Figs. 1 and 2 of the drawing, a flask shaped dielectric member 1 is shown, preferably constructed of boron silicate glass. Such a glass is particularly adapted for

30 high frequency use such as, for example, "Pyrex" or "Nonex" glass. The flask 1 is provided with a re-entrant portion 2. The reentrant portion extends substantially beyond the center of the flask and is terminated by a dome-shaped construction, as indicated at 2. Beyond the dome-shaped portion a long narrow neck 3 is formed. A skirt 4 is formed at substantially the central portion thereof and connects the outer wall portion of the flask 1 with the neck portion 3. At

35 the junction of skirt 4 and the outer cylindrical portion 1, the wall thickness of the dielectric member is substantially increased in thickness at point 5 and provided with a radius 6 which is sufficient to prevent corona discharge at the operating voltage of the condenser. The outer cylindrical portion of flask 1 (starting at radius 6) and the re-entrant portion including dome 2 is coated with a metallic electrode 7 which is preferably formed on the glass by applying a thin coating of silver paste, and then heating the glass to a temperature sufficient to melt the silver and unite it with the glass, which temperature is in the order of 400 to 500 degrees centigrade.

40 45 50 The inner portion of flask 1 is entirely coated with a metallic electrode 8 which is also formed with

a semi-fluid silver paste which is poured in and then the surplus removed, after which it is heated in a manner mentioned above in connection with electrode 7. Electrode 8 terminates just short of the extreme end of the condenser at a point 9. The wall thickness 1 is approximately 2 millimeters thick, and when constructed of special glass for high frequency rectifier use (the condenser being used as a filter condenser) will stand approximately 50,000 volts D. C. at a ripple frequency of about 100 kilocycles and carry current in the order of 200 milliamperes. It is noted that the increased portion of the wall thickness at point 5 is curved in three different directions, the first being formed by radius 6, the second by the curved inner wall and the point 10, which curvature follows substantially the curve of dome 2. The third or outer curvature is formed at point 11. This increased wall thickness is located at a point where the electrostatic stress of the surrounding air is normally most intense, and by this construction the stress is considerably decreased so that all tendency of the formation of corona discharge at this point is substantially eliminated. The provision of the skirt 4 electrically subdivides the creepage path between the outer electrode 7 and inner electrode 8. Furthermore, the shape and arrangement of the upper portion of the flask, starting from point 9 and terminating at the radius of curvature 6 on the inner portion of skirt 4, is such that in event an excess voltage is applied, the condenser will be discharged by an electric arc which will form at this point. The ratio of length of this creepage path and the wall thickness of the glass is such that the arc will discharge before the voltage is built up sufficiently to puncture through the glass wall. In one form of condenser which was constructed in accordance with this invention, the total length of the flask was about 5½ inches long, 2 inches in diameter at the outer portion of the flask, 1¼ inch at the re-entrant portion, and 1⅓ inch at the neck portion, the outer diameter of the skirt being 3¼ inches in diameter and the wall thickness approximately .784 or about 2 millimeters thick. The curvature of radius 6 was equal to about ¼ of an inch. Such a condenser has a capacity of 500 micromicrofarads and will stand 50,000 volts. The cost of a condenser of this type is about one quarter of an equivalent prior art type of the same capacity and voltage rating.

As shown in Fig. 3, the condensers of Fig. 1 are telescoped and connected in series, the connection from the inner electrode 8 being formed by placing a flexible metallic member 12 over the inside metallic coated wall of the re-entrant dome portion 2. This connection 12 may be formed of spring metallic material or flexible "Belden" or stranded copper braid which, as shown by Fig. 1, extends beyond the end of neck portion 3 and terminates in a flexible band 13 and is soldered thereto. The other end is located at and extends beyond the metallic base of dome portion 2. The outer electrode 7 is connected by a split band clamp 14 which clamp may also form a supporting base to be secured to an insulator 15, the clamp 14 being secured to insulator 15 by means of a bolt 16. In order to provide intimate contact between clamp 4 and electrode 7, a soft lead gasket 17 is provided. Likewise, if desired, a soft gasket 18 may be interposed between electrode 7 of the adjacent condenser and member 13. The two ends of the band clamp 14 are clamped together by means of bolt 16 and nut 20.

Fig. 4 shows a modified telescoping method

whereby a telescoping connection is made by placing a resilient stopper 21 of rubber in the neck of the condenser inside the braid 12. The braid 12 is carried beyond the end of neck 3 and clamped by a split end cap 24 which is constructed of spring metal, such as phosphorous bronze, and is provided with bent fingers 24A, the arrangement being such that the bent fingers make a good sliding contact with the outside electrode 1 of an adjacent condenser. A screw 22 and nut 23 retains the end cap 24 in position.

When a connection other than the series arrangement shown by Figs. 3 and 4 is desired, an alternative arrangement shown by Fig. 4B is provided. This method is used as a terminus of the end condenser, or when parallel or non-telescoping arrangements of the device as desired. The construction of the terminal electrode of Fig. 4B includes a resilient rubber stopper member 21A having a central aperture therein through which passes a terminal screw 22A which is provided with a clamp nut 23A. In order to prevent formation of corona at this point and also the entry of dust or moisture, a spherical shaped metallic member 24B is provided. The connection is made by means of a metallic tubing 25. To insure positive connection between the inner electrode 8 and terminal screw 22A, a soft lead gasket 26 is provided between the glass and rubber stopper. Also a metal washer 27 is placed beneath the terminal nut 23 to distribute the pressure on stopper 21 when it is compressed by screw 22A.

Figs. 5 and 6 illustrate the improved voltage tripling circuit wherein the capacitors of this invention are arranged to form a compact circuit structure with other associated apparatus such as, for example, a high voltage Tesla coil 38 which includes a primary winding 31 connected to an alternating current input source 31A which may be that of an oscillator having a frequency of 100 kilocycles. A high voltage secondary winding 32 is located above the primary winding 31 and is supported by an air core tubular insulating member 30A. The output voltage derived at the terminals of the secondary winding 32 is preferably in the order of 30 kilovolts, and as shown in Fig. 5, one side is connected to the cathode of a rectifier tube 33. The rectifier tube 33 is preferably that of the RCA tube 8016 type. The cathode of rectifier tube 33 is connected to the terminal 24B of condenser 1A which is the type shown in Figs. 1 to 4 inclusive. The other side of secondary 32 is connected to ground. The rectifier voltage between plate 33A and ground 33B is approximately 30 kilovolts.

Because the voltage is too high at a point adjacent the rectifier tube 33 and condenser 1A to insure sufficient insulation to the filaments of the rectifier, the ordinary filament heating transformer which is generally employed in lower voltage rectifier circuits cannot be employed. Therefore, in order to heat the cathode or filament at this point, a small resonant circuit, sufficient to heat the rectifier filaments to approximately 200 milliamperes, is provided. This circuit includes an inductance coil 40 of the auto transformer type having a voltage tap 41A. In order to conserve space and reduce the chances of voltage flash-over, the auto transformer 40 is arranged to be wound around the insulating base of the rectifier tube 33. The circuit is brought into resonance by connecting a small variable capacitor 41 to the outer ends of coil 40. The capacitor 41 is preferably secured to a support mounting 42 located adjacent to the base of the rectifier tube.

thus keeping the entire radio frequency substantially well above the ground potential indicated at 33B. The transformer 40 is generally tuned to the fundamental frequency. However, if desired, it may be tuned to a harmonic frequency if the harmonic content is sufficient to permit constant energy to be derived to properly heat the filament of the rectifier tube. The current passing through the transformer 40 is the current passing through the tube capacitance between 10 anode and filament. As shown in Fig. 6, the filament is connected from one side of coil 40 to the tap 41A. A second rectifier tube 34 is supported by an insulating tube 34A, extending out from the re-entrant portion of condenser 1A, and 15 is electrically connected to the outside electrode 7 by the supporting band 14 of one of the capacitors of this invention. The filament or cathode of rectifier 34 is heated by coil 40 and condenser 41 in the same manner as mentioned above in connection with the heating of the rectifier 33. A third rectifier tube 35 also has its anode connected to electrode 7 of condenser 1A. At this point, the voltage from rectifier 34 and ground 33B is now increased to 90 kilovolts; and there is connected in series between the anode of rectifier tube 34 and ground the two condensers 1B and 1C of this invention. A connection is made from band 14 of condenser 1B to the cathode of rectifier 35 and the anode of rectifier 33. The filament of rectifier 35 is heated by an auto-transformer 40 in the same manner mentioned above in connection with rectifier 33, although the tap 41A may be for a different value of voltage and current. Also, if desired, a different type of rectifier may be employed than the previously mentioned rectifiers for the reason that the voltage is substantially increased at this point. It will be noted that by the use of condensers of this invention, the structural arrangement of the high voltage circuit is substantially reduced in physical dimensions over that of the type wherein ordinary condensers are employed. Also the shape and structural features of the condensers 1A, 1B and 1C of this invention permit complete freedom of design, allowing the condensers to be interchanged from a series telescoping arrangement to that of a parallel arrangement with a minimum amount of supporting structure.

The mode of operation of the high frequency high voltage source shown by Figs. 5 and 6 is as follows: A radio frequency voltage of approximately 100 kilocycles and 30 kilovolts is obtained from the alternating current generated source impressed on the Tesla coil 30. The output alternating current voltage from the secondary 32 is rectified by the first rectifier 33, which charges condenser 1C to a peak voltage E of 30 kilovolts. The alternating current generator in series with the condenser 1C charged by rectifier 33 acts in effect as the energizing source for the second rectifier 34, and thus condenser 1A is charged to a double voltage 2E of 60 kilovolts. Rectifier 34 is energized (going from the plate toward the cathode) by the voltages on condenser 1A, the alternating current generator, and the condenser 1C in series. As the polarity of condenser 1C is opposing, the total energizing voltage on rectifier 34 is composed of two parts, one part being equal in magnitude to 2E (due to the voltage on condenser 1A plus the voltage of the alternating current generator), and the other part in an opposing sense, a minus voltage E (on condenser 1C) effectively producing a voltage E on condenser 1B. With respect to ground, however, the 75

cathode of rectifier 34 is at triple potential, or has a voltage 3E of 90 kilovolts. The filament heating auto-transformer 40 receives its current through the alternating current generator 30. It will be seen that the high radio frequency voltage E from the secondary 32 drives a current through the plate-cathode or interelectrode capacitance of the diodes over the respective filter condensers. The radio frequency current flowing through the rectifier interelectrode capacitance is stepped down by the auto-transformer winding 40 which together with the small variable condenser 41 is brought into resonance to obtain the proper value for heating the filament of the rectifiers.

This invention is not to be construed as limited to the modifications described.

What is claimed is:

1. An electric condenser comprising a hollow cylindrical dielectric member having a re-entrant portion, a neck portion having a width such as to permit telescoping of a similar condenser at the re-entrant portion of said similar condenser, a metallic electrode coating on substantially the entire inside wall of said dielectric member and a metallic electrode coating on a portion of the outside wall of said dielectric member.

2. A high electrostatic condenser comprising a hollow cylindrical dielectric member having a re-entrant portion and a neck portion of reduced diameter located above said re-entrant portion, the reduced diameter of said neck portion being such as to permit telescoping of a similar condenser at the re-entrant portion of said similar condenser, a metallic electrode coating on substantially the entire inside wall of said dielectric member and a metallic electrode coating on a portion of the outside wall of said dielectric member.

3. A high voltage electric condenser comprising a glass cylindrical flask having a re-entrant portion extending substantially midway in said flask, a neck portion having a width such as to permit telescoping of a similar condenser at the re-entrant portion of said similar condenser, a metallic electrode coating on substantially the entire inside wall of said flask, a metallic electrode coating on the outside wall of the re-entrant portion of the outside wall and terminating substantially midway on said flask and a thickened glass portion located at the termination of said outside electrode.

4. A high voltage electric condenser comprising two cylindrical walls of dielectric material, said cylindrical walls being connected together at the lower portion thereof, the innermost cylindrical wall being terminated by a dome portion, the outermost cylindrical wall having a skirt portion forming a corona shield for said condenser, a metallic electrode coating on the entire inside wall of both of said cylindrical walls and a metallic electrode coating on the outside wall adjacent said skirt of the outermost cylinder, and the outside wall of said innermost cylinder, including said dome portion.

5. An electric condenser arrangement for a high frequency voltage multiplier circuit comprising a plurality of rectifiers of the electron discharge device type and a plurality of condenser elements having a cylindrical dielectric member with a re-entrant portion, a metallic electrode on the inside walls, a metallic electrode coating on a portion of the outside walls of said dielectric member and at least two of said con-

densers connected in series by a connection made within the re-entrant portion of an adjacent condenser.

6. An electric condenser arrangement for a high frequency voltage multiplier circuit comprising a plurality of rectifiers of the electron discharge device type and a plurality of condenser elements having a cylindrical dielectric member with a re-entrant portion and a long neck portion, a metallic electrode coating on the 10 inside walls of said cylindrical dielectric member, a metallic electrode coating on a portion of the outside walls of said cylindrical dielectric member, and means to provide a connection from the outside electrode portion to the inside electrode portion of an adjacent condenser.

7. An electrostatic condenser for a high frequency voltage multiplier comprising a condenser element having a cylindrical dielectric member with oppositely disposed neck and re-entrant portions, said re-entrant portion extending to a point intermediate the ends of said condenser element, the width of said neck portion being such as to permit the telescoping of a similar condenser element at the re-entrant portion of said similar condenser element, a metallic electrode on the inside wall of said dielectric member, a metallic electrode coating on the outside wall of said re-entrant portion and on a portion of the outside wall of said condenser, a skirt portion located at 30 the termination of the coating on the outside wall of said condenser to form a corona shield to prevent brushing between the inside and outside electrodes.

8. An electric condenser arrangement for high frequency and high voltage use comprising a plurality of condenser elements having cylindrical re-entrant portions, a metallic electrode on the inside wall of said cylindrical dielectric elements, a metallic electric coating on a portion of the 40 outside wall of said dielectric elements, supporting means for said condenser elements, the arrangement being such that adjacent condenser elements telescope within the re-entrant portion so as to provide variation in capacity between 45 adjacent condenser elements.

9. A high voltage rectifier circuit including filter condensers of the type having a hollow cylindrical shape with inner and outer electrodes and a re-entrant portion, a plurality of rectifiers, some of which are insulatingly supported by and connected to some of said condensers at the re-entrant portion thereof.

10. A high voltage rectifier circuit including a plurality of filter condensers and rectifiers, some 55 of said condensers being of the hollow cylindrical type having a re-entrant portion with inner and outer electrodes, the re-entrant portion of said condensers being arranged to support some of said rectifiers and means to heat the filaments of said rectifier by a transformer tuned to the resonant frequency of the input source of said rectifier circuit.

11. A high voltage rectifier circuit including a high voltage oscillation circuit, a plurality of rectifiers connected to said oscillation circuit, a plurality of condensers of the type having a cylindrical flask with a re-entrant portion with inner and outer electrodes, a transformer surrounding and supported by the base of said rectifiers to heat the filaments thereof by being tuned to the resonant frequency of said oscillation circuit, and a plurality of condensers of said first mentioned condenser type connected together in series to 75

form a voltage divider between the output of said rectifier circuit and ground.

12. A high voltage rectifier circuit including a high voltage oscillation circuit, a plurality of rectifiers connected to said oscillation circuit, a plurality of condensers of the type having a cylindrical flask with a re-entrant portion with inner and outer electrodes, a transformer surrounding and supported by the base of said rectifiers and a variable condenser supported by the base of said rectifier tubes to heat the filaments thereof by being tuned to resonant frequency of said oscillation circuit and a plurality of condensers connected together in series to form a voltage divider between the output of said rectifier circuit and ground.

13. A high voltage rectifier circuit including an alternating current input source, a rectifier of the type having a filament and an insulating base, means including an inductive element which is secured to and surrounds said insulating base and which is connected to said filament to heat the filament of said rectifier, said inductive element being tuned substantially to the resonant frequency of the input source of said rectifier circuit.

14. A high voltage high frequency rectifier circuit including a rectifier of the type having a filament, a condenser of the type having a re-entrant portion; said rectifier being insulatingly supported by, electrically connected to and located adjacent said condenser at the re-entrant portion thereof; inductive means to heat the filament of said rectifier; and means capacitively and cooperatively associated with said inductive means to tune said combination substantially to the resonant frequency of the input source of said high voltage high frequency.

15. A high voltage high frequency rectifier circuit comprising an alternating current input source, a tube having a base, said tube being energized by said alternating current, a transformer mounted on said base and having a winding positioned in the neighborhood of said base, and a condenser connected in shunt with said winding for tuning said transformer.

16. In a high voltage high frequency rectifier circuit, a plurality of rectifiers, a plurality of condensers, at least one of said condensers being of the hollow cylindrical type having a neck portion and a re-entrant portion, a first one of said rectifiers insulatingly supporting one end of said one condenser at said neck portion, a second rectifier insulatingly supporting the other end of said one condenser at an end opposite said neck portion, and a third rectifier insulatingly supported at one end by said one condenser at the re-entrant portion, the other end of said third rectifier being insulatingly supported by at least another condenser.

17. A high voltage rectifier circuit operable to rectify currents having high frequency components including a rectifier of the type having an anode and a filament with inter-electrode capacity therebetween, means tuned to resonate at the high frequency components including an autotransformer having an inductive winding and shunt capacitance, said winding including a tapped portion to heat the filament of said rectifier, said transformer winding and shunt capacitance being tuned substantially to the resonant frequency of the input source of said rectifier circuit, means connecting the transformer winding in series with the rectifier anode-filament inter-electrode capacity whereby the high

frequency components that are applied for rectification are effective to energize the transformer, and means connecting said filament to the tapped portion of the inductive winding.

18. A high voltage rectifier circuit for rectifying high frequency components including a rectifier of the type having an anode and a filament with inter-electrode capacity therebetween, a parallel resonant circuit including an inductance and capacitance tuned to the frequency of the applied high frequency components, means connecting the parallel resonant circuit in series with the high frequency components that are applied to the rectifier whereby the high frequency components transmitted by the inter-electrode capacity of the rectifier are effective to energize the tuned circuit, and means connecting the filament of the rectifier across at least a portion of the inductance element of the tuned circuit to thereby energize the filament. 5

19. A high voltage circuit operable to rectify currents having high frequency components including a high frequency source of energy, a rectifier of the type having an anode and a filamentary thermionic electron emitter, a parallel resonant circuit including an inductance and a capacitance tuned to substantially the frequency of the high frequency components, means to apply energy from the high frequency source across the rectifier in series with the tuned circuit whereby the tuned circuit may be energized due to energy passed by the inter-electrode capacity of the rectifier, and means to connect the filamentary electrode emitter across at least a portion of the in- 15 20 25

ductance element of the tuned circuit to supply energy to the filament of the rectifier in order that the applied high frequency energy may be rectified.
